UNITED STATES PATENT OFFICE.

THOMAS J. WAVRUNEK, OF SHAWANO, WISCONSIN.

ADDING AND SUBTRACTING MACHINE.

1,294,853.

Specification of Letters Patent. Patented Feb. 18, 1919.

Application filed November 21, 1917. Serial No. 203,128.

To all whom it may concern:

Be it known that I, THOMAS J. WAVRUNEK, a citizen of the United States, and a resident of Shawano, in the county of Shawano and State of Wisconsin, have invented a new and Improved Adding and Subtracting Machine, of which the following is a full, clear, and exact description.

This invention relates to calculating machines and deals more particularly with machines of that type including a plurality of number-carrying wheels and an operating key associated with each wheel for performing the necessary movements to add or subtract.

The invention has for its general objects to improve and simplify the construction and operation of apparatus of this character so as to be reliable and efficient in use, 20 comparatively simple and inexpensive to manufacture, and so designed that additions or subtractions can be performed by the same keys by reversing the order of manipulating the keys in adding or subtracting; 25 that is to say, in adding a number more than ten the keys are operated from left to right, and in subtracting a number two digits or more the keys are operated from right to left.

30 A more specific object of the invention is the provision of a calculating machine in which the number-carrying wheels have each a row of numbers for adding and subtracting, the numbers reading up from zero to nine, and if desired the wheels may be of such diameter as to have a plurality of groups or series of these numbers, and the operating key for each wheel has a pawl and ratchet means for moving the wheel in 35 one direction with the key, and between adjacent wheels is provided a novel transfer means for transferring from a lower to a higher denomination, this means being of such a design that the key for the wheel of 40 higher denomination will be raised one step by the wheel of lower denomination when the same has made one revolution, so that it is necessary to again operate this raised key to complete the calculation and turn the 45 keys to normal or zero position.

With such objects in view, and others which will appear as the description proceeds, the invention comprises various novel features of construction and arrangement of 50 parts which will be set forth with particu-

larity in the following description and claims appended hereto.

In the accompanying drawings, which illustrate one embodiment of the invention and wherein similar characters of reference 55 indicate corresponding parts in all the views,

Fig. 1 is a plan view of the machine;

Fig. 2 is a vertical section on the line 2-2, Fig. 1, showing the parts in normal 60 position;

Fig. 3 is a similar view showing a key being raised one step for carrying over a calculation into the tens, hundreds or thousands, the normal position of the key being 65 shown by full lines and its raised position by dotted lines;

Fig. 4 is a fragmentary sectional view on the line 4-4, Fig. 3, to show the number wheels, keys and tenths carrying-over device; 70

Fig. 5 is a front view of the machine; and

Fig. 6 is a face view of one of the number wheels drawn on a reduced scale.

Referring to the drawing, A designates a 80 casing of suitable construction which has a portion 1 of its front curved on an arc of a circle, and in this portion are vertical slots 2, and an aperture 3 at the left of each slot and in the slots swing the keys or 85 levers B.

Arranged in the casing A are the number wheels C, there being one for each key B. In the present instance the periphery of each wheel carries a line of numbers 4 for 90 the addition and subtraction calculations, and each line may have a plurality of series of numbers from zero to nine; hence, in the illustration each wheel has three series of ten numbers. The wheels are mounted on 95 a horizontal shaft 6 in such position that the peripheries will be exposed through the openings 3 of the casing. On the casing are two series of numbers 4' and 5' for the addition and subtraction calculations, the 100 addition numbers reading up from one as they do on the number wheels, and the subtraction numbers reading from one down to correspond with the numbers on the number wheels. In other words, as shown in 105 Fig. 5, one is at the bottom of the addition column and nine at the bottom of the subtraction column.

On the right side of each number wheel are pins or ratchet teeth 7, there being one 110

for each number on the periphery of the number wheel, or, in the present instance, there are thirty ratchet teeth on each wheel. The key B is at the right side of its associated wheel and is provided with a spring-pressed pawl 8, which is disposed within the circle of ratchet pins 7, and has its lower end engageable with the said pins. Thus, by moving a key upwardly from the full to the dotted-line position, Fig. 2, the pawl clicks over the ratchet teeth or pins 7, but when the lever is moved downwardly from its raised position the lower end of the pawl engages one of the pins and causes the number wheel to turn with the key when it is depressed. A hold-back pawl 9 co-operates with the ratchet pins to prevent the number wheel from turning with the key as the latter is raised. The pawls 9 are fulcrumed on a bar 10 mounted in the bottom of the casing, and an L-shaped spring 11 operates on the hold-back pawl to yieldingly maintain the same in holding position. On the forward end 12 of each hold-back pawl 9 is an upwardly-extending finger 13 which extends out of the casing A and forms a stop for the key B when the latter is pressed downwardly to zero position. The hold-back pawl stops the wheel in its proper position when the key is depressed, since the key throws the rear end of the pawl upwardly to engage between two of the teeth 7 and thereby prevent the wheel from over-traveling, due to momentum. In other words, the pawl 9 performs the function of a brake during forward travel of the wheel and of a stop for preventing the rearward travel of the wheel with the raising of the key.

Between adjacent number wheels is a tenths carrying-over device which comprises a lever 14 fulcrumed at 15 in the rear of the casing and extending upwardly between the number wheels, and on the upper end of the lever is a curved extremity 16 terminating in a hook 17 which engages under the corresponding key B. The extremity 16 rests on the shaft 6, or, more properly, the spacing sleeve 18 between adjacent number wheels, and in this position the hook 17 is in close proximity to or engaged with the under edge of the key B, as clearly shown in Fig. 3. Obviously, if the lever 14 is raised, the key B will move with it, and this occurs when a number wheel of lower value moves ten steps. The movement of the lever 14 is effected by any one of three pins 19 on the left face of each number wheel. The pin 19 engages an offset tooth 20 on the lever 14, the tooth 20 being so designed that the pin 19 will wipe past the tooth 20 after raising the lever 14 far enough to lift the key B one step or the distance between two adjacent ratchet teeth. This operation will be clear from Fig. 3, where the pin 19 has moved from the position *a* to the position *b*, and in doing so

it has raised the lever 14 from the full to the dotted line position, and this lever has correspondingly raised the key B one step.

Normally the keys are in the position shown in Fig. 5, with the zeros of the number wheels showing through the view openings 3 in the casing. Let it be assumed that the two numbers 742 and 281 are to be added. The first three keys to the right are raised respectively to the numbers 7, 4 and 2 on the addition columns 4' of the casing. The levers are then depressed one at a time, beginning with the lever at the left and ending at the right. The three levers are again raised to the numbers 2, 8 and 1, respectively, and depressed in the same order as before and one at a time. During this operation the lever 14 associated with the second or tenths wheel causes the third key, or the first key to the left that was operated, to be raised one step, so that this key must be further depressed, which causes the third lever 14 to raise the fourth key one step, so that when this fourth key is depressed the operation will be completed, and on the machine will be registered the total of 1023.

In subtracting it is merely necessary to raise the key to the number in the right-hand column, headed "Sub," that is to be subtracted, and then depress the lever to zero position. For instance, if it is desired to subtract one from five, the key will be raised to the number "1" and then the key depressed, when "4" will be exposed at the view opening 3. If seven is to be subtracted from eight, the key is raised to the number "7" and depressed, when the number "1" will appear at the opening 3.

From the foregoing description taken in connection with the accompanying drawings, the advantages of the construction and method of operation will be readily understood by those skilled in the art to which the invention appertains, and while I have described the principle of operation, together with the apparatus which I now consider to be the best embodiment thereof, I desire to have it understood that the apparatus shown is merely illustrative and that such changes may be made when desired as fall within the scope of the appended claims.

Having thus described my invention, I claim as new and desire to secure by Letters Patent:

1. A calculating machine comprising a casing having pairs of columns of numbers, the numbers of one column reading reversely to the numbers of the associated column, a key movable along each pair of columns, a number-wheel operated by each key and having numbers from zero to nine, and a tenths carrying-over device between a wheel of lower value and the key for the next higher value wheel and having means engaged by the wheel of lower value once

- in each revolution thereof, whereby the associated key is moved from zero position one unit and must be manually returned to normal position to complete the calculation.
5. 2. A calculating machine of the class described comprising a casing having groups of two sets of numbers from zero to nine, and one set reading reversely to the other for addition and subtraction respectively, a number bearing wheel for each group of numbers, a key for operating each wheel, and a tenths carrying-over device between a wheel of lower value and the key for the next higher value wheel, whereby such key is moved forwardly one unit and must be manually actuated to complete the calculation, said device including a member engaging the key when the latter is in normal position, and means on the adjacent wheel for engaging and wiping by the member when the said wheel has moved ten units.
10. 3. A calculating machine comprising a plurality of groups of number columns of ten addition numbers and ten subtraction numbers reading oppositely to the addition numbers, a wheel having numbers from zero to nine, a key for each wheel, a ratchet and pawl mechanism between the key and adjacent wheel, a lever normally engaging each key and adapted to remain in normal position while the key is manually operated, and means on each wheel for engaging the lever of the key of the next wheel to move such key one step when the number wheel moves ten steps.
15. 4. A calculating machine comprising a plurality of number-carrying wheels, a shaft supporting the wheels, keys mounted on the
20. shaft, a ratchet and pawl device between each key and adjacent wheel, levers having 40 their free ends normally bearing on the shaft and engaging under the keys, and means on the number wheels for actuating the levers, whereby a key is moved one step each time the wheel of next lower value 45 moves ten steps.
25. 5. A calculating machine comprising a plurality of number-carrying wheels, a shaft supporting the wheels, keys mounted on the shaft, a ratchet device between each key and 50 adjacent wheel, a lever associated with each key and fulcrumed at a point beyond the wheels and extending across the top of the shaft to normally bear thereon, and each lever having a hook for engaging under the 55 associated key, and means on each wheel for engaging and lifting the associated lever for lifting the associated key one unit movement for every ten unit movements of the wheel. 60
30. 6. In a calculating machine, the combination of a number-carrying wheel having numbers on its periphery, teeth projecting from the face of the wheel and spaced correspondingly to the numbers on the wheel, 65 said teeth being arranged within a circle, a key associated with the wheel, a pawl pivoted on the key and disposed within the circle of teeth, spring means for urging the pawl outwardly to engage the teeth, a hold-back pawl pivoted at a point beyond the teeth and normally engaging the latter, and a member carried by each hold-back pawl and forming a stop for the adjacent key when in zero position. 70
